U.S. Cl. 424—71

4 Claims

ABSTRACT OF THE DISCLOSURE

Hair wax compositions comprising:

- (a) A plastic partial glyceride of fatty acid;
- (b) A hard partial glyceride of fatty acid;
- (c) A polyoxyethylene ether of a monoester of a hexitan and a fatty acid;
- (d) A monoester of a polyethylene glycol;
- (e) A polyoxyethylene ether;
- (f) A wax having a melting point of 120° F. to 190° F.

The present invention relates to hair grooming agents, and more particularly, to water-soluble washable hair wax compositions.

Hair waxes for use on short hair, that is crew-cuts, have been known and sold for many years. Although these prior hair waxes are effective grooming aids, they are insoluble in water, non-washable, and therefore are difficult to remove from combs, hair brushes, hat bands, pillow cases, etc. A water-soluble, washable hair wax for crew-cuts has now been developed in accordance with the present invention that overcomes the aforementioned difficulties. The hair wax of the present invention is readily soluble in water and can be easily removed from the hair or from combs, brushes, etc. by simply washing with water.

The water-soluble washable hair wax composition of the present invention comprises:

(a) 10 to 20 percent by weight of a plastic partial glyceride of fatty acid containing from 14 to 18 carbon atoms and having a monoester content of 40 to 70% and an iodine value of from 35 to 70;

(b) 10 to 20 percent by weight of a hard partial glyceride of fatty acid containing from 14 to 18 carbon atoms and having a monoester content of 40 to 70% and an iodine value less than 20;

(c) 15 to 25 percent by weight of a polyoxyethylene ether of a monoester of a hexitan and a fatty acid containing from 12 to 18 carbon atoms, said ether containing from 15 to 25 oxyethylene groups per mol;

(d) 10 to 20 parts by weight of a monoester of a polyoxyethylene glycol containing from 40 to 150 oxyethylene groups and a saturated fatty acid containing from 14 to 18 carbon atoms;

(e) 20 to 40 parts by weight of a polyoxyethylene ether, containing from 15 to 25 oxyethylene groups, of an alcohol containing from 14 to 18 carbon atoms; and

(f) 3 to 8 parts by weight of a wax having a melting point of 120° F. to 190° F.

2

The partial glycerides designated as (a) and (b) above, can be prepared by the glycerolysis of edible fats or by the direct esterification of glycerol and fatty acids containing from 14 to 18 carbon atoms, such as oleic acid, palmitic acid, stearic acid, myristic acid, and the like. The product is a mixture of monoester and diester. The difference between (a) and (b) is that (a) is a plastic glyceride having an iodine value of from 35 to 70 and (b) is a hard glyceride having an iodine value of less than 20.

Typical examples of (c) are polyoxyethylene (20) sorbitan monostearate, polyoxyethylene (20) sorbitan monopalmitate, polyoxyethylene (20) sorbitan monolaurate, polyoxyethylene (20) sorbitan monooleate, polyoxyethylene (15) sorbitan monostearate, polyoxyethylene (25) sorbitan monolaurate, and the like. As is well understood in the art, the number in parenthesis indicates the average number of oxyethylene groups in the molecule.

Typical examples of (d) are polyoxyethylene (40) stearate, polyoxyethylene (50) stearate, polyoxyethylene (100) stearate, polyoxyethylene (150) stearate, polyoxyethylene (125) palmitate, polyoxyethylene (75) palmitate, polyoxyethylene (100) myristate, and the like.

Typical examples of (e) are polyoxyethylene (15) cetyl ether, polyoxyethylene (20) cetyl ether, polyoxyethylene (25) cetyl ether, polyoxyethylene (20) stearyl ether, polyoxyethylene (22) stearyl ether, polyoxyethylene (20) tetradecyl ether, polyoxyethylene (25) pentadecylether polyoxyethylene (20) heptadecyl ether, and the like.

The wax component of the composition may be of natural or synthetic origin. Suitable waxes include paraffin wax, ceresin, beeswax, carnauba wax, and the like.

Preferred water-soluble hair waxes of the present invention comprise:

(a) 15 parts by weight of plastic partial glycerides of fatty acids containing from 14 to 18 carbon atoms and having a monoester content of about 42% and an value of about 60;

(b) 15 parts by weight of hard partial glycerides of fatty acids containing from 14 to 18 carbon atoms and having a monoester content of about 42% and an iodine value of less than 5;

(c) 20 parts by weight of polyoxyethylene (20) sorbitan monostearate;

(d) 15 parts by weight of polyoxyethylene (100) stearate;

(e) 30 parts by weight of polyoxyethylene (20) cetyl ether; and

(f) 5 parts by weight of household paraffin wax.

The hair wax compositions of the present invention are readily prepared by melting all the ingredients together at about 70° C., agitating, and cooling. The melt may, if desired, be cast directly into cylindrical molds and cooled, to produce sticks of wax suitable for package in push-up stick cylinders for convenient application to the hair.

In the following illustrative examples, the indicated ingredients are heated to 70° C., agitated, poured into a mold and cooled. The resulting hair waxes provide good grooming, light color, high melting points, rapid wash-

ability, and do not separate on melting or freezing. All percentages stated are by weight unless otherwise specified.

Example 1

	Percent	5
Mono- and diglyceride from lard fatty acids. 42% monoester. Iodine value 60	15	
Mono- and diglyceride of hydrogenated soya fatty acids. 42% monoester. Iodine value 3	15	
Polyoxyethylene (20) sorbitan monostearate	20	10
Polyoxyethylene (100) stearate	15	
Polyoxyethylene (20) cetyl ether	30	
Household paraffin wax	5	

Example 2

	Percent	15
Mono- and diglyceride of mixture of lard fatty acids. 42% monoester. Iodine value 60	10	
Mono- and diglyceride of mixture of hydrogenated soya fatty acids. 42% monoester. Iodine value 4	12	20
Polyoxyethylene (20) sorbitan monopalmitate	15	
Polyoxyethylene (40) myristate	20	
Polyoxyethylene (20) stearyl ether	40	
Beeswax	3	

Example 3

	Percent	25
Mono- and diglyceride of mixture of C ₁₄ -C ₁₈ fatty acids. 40% monoester. Iodine value 70	20	
Mono- and diglyceride of mixture of C ₁₄ -C ₁₈ fatty acids. 70% monoester. Iodine value 15	10	30
Polyoxyethylene (25) sorbitan monolaurate	25	
Polyoxyethylene (150) stearate	10	
Polyoxyethylene (25) cetyl ether	27	
Carnauba wax	8	

Example 4

	Percent	35
Mono- and diglyceride of tallow fatty acid. 70% monoester. Iodine value 35	10	
Mono- and diglyceride of partially hydrogenated cottonseed oil acids. 70% monoester. Iodine value 10	40	
Polyoxyethylene (15) sorbitan monomyristate	20	
Polyoxyethylene (100) palmitate	15	
Polyoxyethylene (15) cetyl ether	30	
Paraffin wax	5	45

The water-soluble washable hair wax of the present invention may also contain cosmetically acceptable adjuncts, added for their known purpose. Among such may be named colorants, medications, lanolin, perfume, and the like.

What is claimed as new and desired to be protected by Letters Patent of the United States is:

1. Water-soluble hair wax composition comprising:

- (a) 10 to 20 percent by weight of a plastic partial glyceride of fatty acid containing from 14 to 18 carbon atoms and having a monoester content of 40 to 70% and an iodine value of from 35 to 70;
- (b) 10 to 20 percent by weight of hard partial glyceride of fatty acid containing from 14 to 18 carbon atoms and having a monoester content of 40 to 70% and an iodine value less than 20;
- (c) 15 to 25 percent by weight of a polyoxyethylene ether of a monoester of a hexitan and a fatty acid containing from 12 to 18 carbon atoms said ether containing from 15 to 25 oxyethylene groups per mol;
- (d) 10 to 20 percent by weight of a monoester of a polyethylene glycol containing from 40 to 150 oxyethylene groups and a saturated fatty acid containing from 14 to 18 carbon atoms;
- (e) 20 to 40 percent by weight of a polyoxyethylene ether, containing from 15 to 25 oxyethylene groups, of a saturated aliphatic alcohol containing from 14 to 18 carbon atoms; and

(f) 3 to 8 parts by weight of a wax having a melting point of 120° F. to 190° F.

2. Water-soluble hair wax composition comprising:

- (a) 15 percent by weight of plastic partial glycerides of fatty acid containing from 14 to 18 carbon atoms and having a monoester content of 40 to 70% and an iodine value of from 35 to 70;
- (b) 15 percent by weight of hard partial glycerides of fatty acid containing from 14 to 18 carbon atoms and having a monoester content of 40 to 70% and an iodine value less than 20;
- (c) 20 percent by weight of a polyoxyethylene ether of a monoester of a hexitan and a fatty acid containing from 12 to 18 carbon atoms, said ether containing from 15 to 25 oxyethylene groups;
- (d) 15 parts by weight of a monoester of a polyoxyethylene glycol containing from 40 to 150 oxyethylene groups and a saturated fatty acid containing from 14 to 18 carbon atoms;
- (e) 30 parts by weight of an ether of a polyoxyethylene ether, containing from 15 to 25 oxyethylene groups, of a saturated aliphatic alcohol containing from 14 to 18 carbon atoms; and
- (f) 5 parts by weight of a wax having a melting point of from 120° F. to 190° F.

3. Washable hair wax composition comprising:

- (a) 10 to 20 percent by weight of a plastic partial glyceride of fatty acid containing from 14 to 18 carbon atoms and having a monoester content of about 42% and an iodine value of about 60;
- (b) 10 to 20 percent by weight of a hard partial glyceride of fatty acid containing from 14-18 carbon atoms and having a monoester content of about 42% and an iodine value of less than 5;
- (c) 15 to 25 percent by weight of polyoxyethylene (20) sorbitan monostearate;
- (d) 10 to 20 percent by weight of polyoxyethylene (100) stearate;
- (e) 20 to 40 percent by weight of polyoxyethylene (20) cetyl ether; and
- (f) 3 to 8 percent by weight of household paraffin wax.

4. Washable crew-cut hair wax composition comprising:

- (a) 15 percent by weight of a plastic partial glycerides of fatty acid containing from 14 to 18 carbon atoms and having a monoester content of about 42% and an iodine value of about 60;
- (b) 15 percent by weight of hard partial glycerides of fatty acid containing from 14-18 carbon atoms and having a monoester content of about 42% and an iodine value of 3;
- (c) 20 percent by weight of polyoxyethylene (20) sorbitan monostearate;
- (d) 15 percent by weight of polyoxyethylene (100) stearate;
- (e) 30 percent by weight of polyoxyethylene (100) cetyl ether; and
- (f) 5 percent by weight of household paraffin wax.
